WALLACE L. CLAYPOOL, OF DAVENPORT, IOWA, ASSIGNOR TO WESTCO-CHIPPEWA PUMP COMPANY, OF DAVENPORT, IOWA, A CORPORATION OF DELAWARE

ROTARY PUMP

Application filed December 19, 1930. Serial No. 503,506.

This invention relates to rotary pumps, and more particularly to an improved casing for rotary pumps having an annular pressure-developing channel.

5 One of the objects of the present invention is to provide a pump of the character described with simple means for increasing the efficiency thereof.

Another object is to provide a casing for 10 a pump of the character described with means for relieving the pressure at the stuffing boxes which are disposed directly against the pressure in the inner chamber that lies inwardly of the pressure-developing channel.

15 Another object is to provide a casing for a pump of the character described which relieves the pressure against the stuffing boxes, so that the stuffing box packing need not be held so tightly around the pump shaft that 20 scoring of the shaft may result.

Another object is to provide a casing for 25 a pump of the character described with a bypass between the inner chamber and the suction side of the pressure-developing channel in order to reduce the pressure in the inner chamber to substantially suction pressure, thereby eliminating the necessity of packing the rotor shaft against the discharge pressure.

30 With the above and other objects in view which will be readily apparent from the following detailed description, the present invention consists in certain features of construction and combination of parts which 35 will be readily understood by those skilled in the art to which the invention appertains.

In a pump of the character described having 40 a circumferential pressure-developing channel that is defined by the cooperative relation of the sides of the pump casing and web of the pump rotor, there is a considerable difference in pressure between the pressure-developing channel and the inner chamber 45 surrounding the rotor shaft that lies inwardly of the pressure developing channel. Any leakage from the pressure-developing channel into the inner channel surrounding the pump shaft has a tendency to force its way 50 into the suction side of the pressure-develop-

ing channel, due to the differences in pressures.

Because of the close clearance between the opposed flanges of the casing and the rotor, there is a pressure built up in the inner chamber which communicates directly with the stuffing boxes. In this type of pump it has been necessary to exert a relatively high packing pressure on the stuffing box packing in order to prevent leakage of liquid 60 through the stuffing boxes, and the consequent injury to the stuffing boxes. This is quite objectionable because of the tendency of the tight packing to score the rotor shaft and because of the production of excess friction, which reduces the efficiency of operation of the pump. Leakage is wasteful and presents a fire hazard when the pump is handling inflammable liquids such as gasoline, petrol products, etc.

70 The present invention contemplates, in order to overcome these disadvantages, the use of a by-pass from the inner chamber to the suction side of the pressure-developing channel to relieve the pressure in the inner chamber and so that suction pressure only will prevail in the inner chamber, therefore making it necessary to pack against suction pressure only and not against the discharge pressure.

75 Referring to the accompanying drawings, in which like numerals refer to like parts throughout the several views,

Figure 1 is an end elevation of one type of pump embodying the present invention, 80 a portion of the pump casing being broken away to show the pump passageways and the stuffing box in section;

Fig. 2 is a view of the pump with the removable casing portion removed to show the 85 rotor and the pump passageways, a portion of the rotor being broken away to show the entrance of the by-pass into the inner chamber surrounding the pump shaft;

Fig. 3 is a section of the pump taken substantially on the line 3-3 of Fig. 1, showing the by-pass leading to the suction side of the pump;

Fig. 4 is a view similar to Fig. 2, showing the use of a modified form of by-pass between 90 100

the pressure-developing channel and the inner chamber;

Fig. 5 is a section taken substantially on the line 5—5 of Fig. 4;

5 Fig. 6 is a view showing the hook-up for an installation embodying two pumps to provide a multiple-stage system; and

Fig. 7 is a side elevation of the installation shown in Fig. 6.

10 The embodiment of the invention that I have chosen to illustrate in the drawings comprises a pump casing formed of mated casing portions 1 and 2 that are connected by means of outwardly extending flanges 3 and 15 4 that are held together by suitable screws 5. Each of the casing portions 1 and 2 has an outwardly extending tubular boss 6 and has a suitable adjustable packing gland 7 mounted therein to retain the packing 7a 20 about the rotor shaft 8 to prevent leakage between the respective casing portions. It is to be noted that the packing gland 7 is threaded into the opening of the boss 6 surrounding the shaft 7 so that the packing 7a can 25 be compressed about the rotor shaft 8.

The rotor 9 is secured to the shaft 8 by a suitable key 10, and the shaft is supported in suitable out-board bearings 11 and is provided with an extension to provide a suitable 30 driving means. The out-board bearings 11 are supported by upper and lower arms 11a and 11b, respectively, which are formed integral with the casing portions 1 and 2. A deformable packing ring 13 is mounted in 35 registered annular grooves 14 in the casing portions to prevent leakage between the casing portions.

The pump assembly is supported on pedestals 15 that are formed on the portions 1 40 of the casing.

Projecting inwardly from each of the casing portions 1 and 2 are opposed annular ribs or flanges 16 which, in cooperation with the web 17 of the rotor 9, define the pressure developing passageway 18 of the pump.

55 Radially extending portions 20 of the flanges 16 of the casing portions 1 and 2 extend across the passageway 18 as far as the outer edge of the rotor buckets to form a deflecting abutment and restriction in the pressure-developing passageway of the pump. This abutment directs the flow of liquid from the pressure passageway 18 through an outlet port 21.

55 The space between the flanges 16 of the mated casing portions is only sufficient to permit unrestricted operation of the motor web 17 therebetween, thus preventing any substantial radial flow of liquid from the pressure-developing passage of the pump inwardly along the web of the rotor. The cooperating extended portions 20 restrict the pressure of the passageway at the outlet end thereof to substantially the cross-sectional dimension of the pump rotor, only sufficient clear-

ance being provided to permit the unrestricted operation of the rotor buckets between them. Direct flow of the liquid from the outlet to the inlet passage is thus prevented.

70 The rotor 9 of the pump comprises a hub portion 22 that is mounted on the drive shaft 8 by means of the key 10, the web 17 which substantially fills the space between the opposed casing flanges 16, and a rim portion 75 having a series of buckets 24 formed therein by transverse partitions 25.

75 The inlet and outlet passageways 26 and 27, respectively, are formed in oppositely extending horizontal portions of the fixed casing portion 1, as shown in Figs. 1 and 2, the removable casing portion 2 being so designed as to unite with the fixed casing portion 1 and cause the proper direct communication of the inlet and outlet passageways 26 and 27 with the pressure-developing channel. The main portion 1 of the pump casing has the cylindrical sleeve 28 formed therein, and the inlet passage 26 opens into the cylindrical side wall of the sleeve 28 in registered relation with a continuation of the passage that is formed in the main casing 1.

80 The removable casing part 2 has a cylindrical face 29 that fits snugly within the sleeve 28 of the main casing. The continuation of 85 the inlet passage 26 is formed by the spirally arranged passage that opens into the face 29 of the casing part 2 and also opens laterally into the casing face 30 that constitutes the defining wall of the pressure-developing channel. The sleeve 28 of the main casing overlies a portion of the curved passage to thereby form the remaining wall of the pressure-developing passage or channel. The inlet port opens laterally into the pressure-developing channel immediately adjacent the extension 20 of the annular flange 16 that defines the inner wall of the pressure-developing channel.

105 From the above description of the elements 110 of the pump, it will be seen that liquid flows into the pump through the inlet 26 to inlet ports located on opposite sides of the rotor. After entering the pressure-developing channel 18 of the pump, the liquid is engaged by 115 the liquid-engaging pockets of the pump rotor and carried completely around the pressure-developing channel to the point where it is deflected tangentially from the pressure-developing channel of the pump by 120 the abutments 20 that closely fit the bucket portion of the rotor and merge into one wall of the outlet passage 27. The outlet port 21 is formed in the outer peripheral wall of the 125 pressure-developing channel 18 and serves to convey the liquid through the outlet in substantially a tangential direction relative to the direction of flow through the pressure-developing channel of the pump. Unnecessary deflection of the liquid in its passage 130

from the pressure side of the pump to the distributing system is thereby avoided.

Referring to Figs. 1, 2 and 3, it will be noted that the chamber 40 surrounding the hub 22 of the rotor 9 and rotor shaft 8 and lying inwardly of the circumferential flanges 16 formed on the pump casings 1 and 2, is placed in direct communication by means of a suitable conduit 41 with the suction side 10 of the pump. The conduit 41 is threaded at its opposite ends into the wall of the casing portion 1 defining the inner chamber 40 and into the wall of that portion of the casing 1 which defines the inlet passage 26. As previously mentioned, any leakage from the pressure-developing channel into the inner chamber 40 has a tendency to force its way into the suction side of the pressure-developing channel, due to the differences in pressure, and, because of the close clearance between the casing portions and the rotor, there is a pressure built up in the area comprising the inner chamber 40 which communicates directly with the stuffing box packing 7a. This discharge pressure within the inner chamber 40 is relieved by the by-pass formed by the conduit 41 so that only a suction pressure prevails within the chamber 40, therefore making it necessary to pack against the suction pressure only. It has been necessary, heretofore, as previously explained, to pack the pump against the discharge pressure and it is obvious that very material advantages can be obtained by employing the by-pass 41 35 from the inner chamber to the suction side of the pump. It is therefore unnecessary to exert a great deal of pressure on the stuffing box, with the result that the pump shaft will rotate with much greater ease and thereby 40 will be increased the efficiency of the pump since the friction is reduced to a minimum.

Another advantage is that, by the use of the by-pass from the inner chamber to the suction side of the pump, the pump shaft will 45 not be scored by the use of relatively large pressures being exerted on the packing glands.

Further advantages are that the waste of valuable liquids such as calcium chloride 50 brine, refinery products, etc., is prevented, and furthermore, that fire hazards are eliminated when inflammable liquids are being pumped.

Referring to Fig. 4, it will be noted that 55 a modification of the pump structure shown in Figs. 1 and 2 is shown. In this construction a passageway 44 is formed in the rib 16 of the fixed casing portion 1, which causes a direct communication from the inner chamber 60 to the pressure-developing channel substantially at the entrance of the inlet passage 26 into the pressure-developing channel. The function of this construction is identically the same as that in the pump construction in Figs. 1 and 2. A corresponding by-

pass may also be formed in the rib of the casing portion 2.

In Figs. 6 and 7 I have shown a construction wherein a two-stage pressure system is employed comprising two separate pumps 70 50 and 51, the first stage being created by the pump 50 and the second stage by the pump 51. In this construction the discharge of the pump 50 is connected by means of the conduit 52 to the inlet side 53 of the pump 51. The inner chamber of the pump 50 is placed in communication by conduits 54 with the suction side 54a of the pump in the same manner as described in connection with Figs. 1 and 2. The inner chamber of the pump 51 is also provided with by-pass conduits 55 which join into a conduit 56 leading directly to the suction side 54a of the pump 50 as shown in Fig. 6. As previously described, the pressures within the inner chamber surrounding the rotors of the pumps 50 and 51 are reduced to substantially suction pressure, since these chambers are placed in direct communication with the suction side of the primary- or first-stage pump 50. 80

It will be noted, however, that in all of the constructions only a suction pressure will prevail within the inner chamber because of the by-pass to the suction side of the pump, and that in these cases it is not necessary to pack against the discharge pressure of the pump, since only the suction pressure prevails in the inner chamber. 95

Aside from the specific embodiments of the invention herein shown and described, it will be understood that numerous details of the construction may be altered or omitted without departing from the spirit or scope of this invention, and I do not desire to limit the invention to the exact construction herein set forth as I desire to claim the same broadly as well as specifically, as indicated in the appended claims. 100

What I claim is:

1. A rotary pump comprising a casing having a circumferential pressure-developing channel and inlet and outlet passages communicating with said channel, a rotary shaft extending through said casing, a rotor mounted on said shaft, buckets formed on the periphery of said rotor and lying within said channel, annular ribs on said casing engaging the sides of said rotor with a running fit for closing in said channel and providing a chamber around said shaft, packing glands carried by said casing and surrounding said shaft, and a by-pass between the suction side of said channel and said chamber for relieving the pressure within said chamber created by the pressure of liquid discharged from said channel, said by-pass comprising a recess in one of said ribs opening at one end into said chamber and at the other end into said channel substantially at the suction side thereof. 110 115 120 125 130

2. A rotary pump comprising a casing having a circumferential pressure-developing channel and inlet and outlet passages communicating with said channel, a rotary shaft 5 extending through said casing, a rotor mounted on said shaft, buckets formed on the periphery of said rotor and lying within said channel, annular ribs on said casing engaging the sides of said rotor with a running 10 fit for closing in said channel and providing a chamber around said shaft, packing glands carried by said casing and surrounding said shaft, and a by-pass in one of said annular ribs extending from said chamber and opening 15 into said channel substantially at the suction side thereof for maintaining a low pressure in said chamber.
3. A rotary pump comprising a casing having a circumferential pressure-developing 20 channel and peripheral inlet and outlet passages communicating with said channel, a rotary shaft extending through said casing coaxial with said channel, a rotor fixed to said shaft and having peripheral buckets lying within said channel, annular ribs on said casing engaging the sides of said rotor with a running fit for closing in said channel and providing a chamber around said shaft, packing glands carried by said casing and surrounding 25 said shaft, and a recess in one of said ribs placing said chamber in communication with said channel substantially at the opening of said inlet passage into said channel to maintain a low pressure in said chamber.
4. A rotary pump comprising a rotor having a web portion and a peripheral bucket portion, a casing enclosing said rotor, means in said casing defining a peripheral pressure-developing channel wherein fluid is engaged 30 by said bucket portion, said means being in running engagement with said web portion, a chamber in said casing radially inwardly of said channel, a rotary shaft extending through said chamber for supporting and rotating said rotor, peripheral suction and discharge passages in said casing opening directly into said channel, stop portions in said channel for diverting fluid in said channel 35 into said discharge passage, and a passageway in said means opening into said channel substantially adjacent said suction passage and opening into said chamber whereby to maintain the pressure in said chamber substantially at suction pressure.

In testimony whereof I affix my signature.
WALLACE L. CLAYPOOL.
